UNITED STATES PATENT OFFICE.

STEFAN STRELAK, OF CHICAGO, ILLINOIS.

DESIGN FOR A KETTLE-COVER HOLDER.

52,356.

Specification for Design.

Patented Aug. 27, 1918.

Application filed June 13, 1917. Serial No. 174,628. Term of patent 3½ years.

To all whom it may concern:

Be it known that I, STEFAN STRELAK, a citizen of the United States, residing in Chicago, in the county of Cook and State of Illinois, have invented a new, original, and ornamental Design for a Kettle-Cover Holder, of which the following is a specification, reference being had to the accompanying drawing, forming part thereof.

Fig. 2 is a side view of Fig. 1.

Fig. 3 is a bottom plan view.

I claim:

The ornamental design for a kettle cover holder, as shown.

In witness whereof, I have hereunto subscribed my name this 7th day of June, 1917.

STEFAN STRELAK.
